UNITED STATES PATENT OFFICE.

GEORGE ARRAS, OF CHICAGO, ILLINOIS.

ELECTRIC-FIXTURE CLAMP.

Application filed June 17, 1926. Serial No. 116,527.

This invention relates to a fixture clamp, particularly for electric fixtures, which is adapted to engage fixture sockets, plugs and the like of different sizes without any variation of the engaging means thereof. The object of the invention is, therefore, to provide a fixture of this kind which is easily operable for engaging plugs or sockets of different sizes. A further object of the invention is to provide an improved simple fixture clamp which automatically centers itself with respect to the device to which it is applied. The invention consists in the novel construction, combination and arrangement of the parts.

In the accompanying drawing, Figure 1 is a side elevation illustrating the invention as applied to an electric lamp fixture plug; Figure 2 is a sectional view of the fixture clamp; Figure 3 is a side elevation of one side of the fixture clamp; and Figure 4 is an enlarged detail of the fastening or clamping means.

In attaching a globe or shade holder to a lamp socket or plug, it is desirable to have a clamp which will accommodate plugs of various sizes, or may even be applied to plugs, sockets and like of entirely different or a variety of sizes. The present invention is designed and intended to provide such a variation that it may easily accommodate different sizes of the same kind of plugs or sockets having a variation of a considerable extent, and at the same time to present means for automatically centering the fixture with respect to the support, so that it will be practical in construction and attractive in appearance.

In carrying out this invention, the clamp proper comprises two strips 5 and 6 of flexible metal of suitable strength, such as steel, copper, phosphor bronze or the like, the ends of which are perforated and secured together by means of staples or eyelets 7 and the intermediate portions of which are formed with oppositely disposed cutouts 8 and 9 adapting the strips to cross each other intermediate the ends thereof, so that the inner ends will form a reduced loop within an outer loop made by the opposite ends of the strips 5 and 6.

In order to confine and suitably support the clamping strips, a hollow shell or housing 10 is provided with an opening 11 through which the connected ends of the strips are inserted, and the opposite side of

the housing is formed with perforations 12 and 13 through which the crossed or reduced portions are inserted, so that the outer end of each strip bears on the outer portion of the shell from the opening 11 to the openings 12 and 13 for holding these portions of the strips in distended position.

In order to clamp these strips about a socket 14, a screw 15 is inserted through the eyelets and perforated ends of the strips and a nut 16, or similar fastening device, is threaded up tightly on the screw. By making the screw of suitable length, variation of the size of the inner loop can be made as large as desired to accommodate sockets or plugs of various sizes and of suitable variation. This inner loop being formed by the strips crossing each other, automatically centers a socket in the holder or housing 10, and if desired, the strips may be formed with a straight portion 17 at their inner ends to more accurately center the parts.

This clamp may be applied to any kind of a shell or shade holder 18, as shown in Figure 1, of which the upper shell or housing 10 is a part, and the globe or shade 19 may be supported by the holder. This suggests only one of a number of uses to which a device of this kind may be applied, it being well understood in the art to which this relates that the fixture clamp proper may be utilized in a number of similar locations with respect to the fixture parts. The clamp itself is simple in construction and operation, not likely to get out of order, and is practically self-centering and self-adjusting for sockets and plugs of different sizes, it being necessary only to vary the fastening nut screw in order to make suitable variations of the clamp.

I claim:

1. A fixture clamp comprising two flexible metal strips secured together at the ends and crossing each other intermediate the ends, a perforated housing through which the strips extend, and fastening means for drawing the connected ends together about a device to which the strips are applied.

2. In a clamp of the class described, a pair of strips connected together at the ends and crossed intermediate the ends, a perforated housing to engage the outer portions of the strips, the inner portions thereof extending within the housing and forming a reduced loop, the ends of the strips being outside of the housing, and means engaging the ends

for drawing them together to vary the size of the inner loop portion.

3. In a fixture clamp, a pair of flexible strips connected together at the ends and crossing intermediate the ends, means comprising a housing for holding the outer portions of the strips in distended position, and fastening means for engaging the connected ends of the strips for varying the loop formed by the inner ends of the strips.

4. In a fixture clamp, a pair of flexible strips of substantially the same length connected together at the ends and having reduced portions intermediate their ends adapting them to be crossed to form an inner clamping loop within the outer portions of the strips, a perforated housing with portions of the strips inside and outside thereof, and means for drawing the ends of the strips together to vary the size of the inner clamping loop.

5. In a fixture clamp, an outer perforated shell, a pair of flexible strips having reduced portions adapting them to be crossed intermediate their ends and connected together at the ends, the outer portions of the strips engaging the outer face of the shell and extending through the perforations so that the inner portions thereof form a partially closed loop, the connected ends of the strips being disposed without the shell, and means for drawing the ends of the strips together to vary the inner loop portion thereof.

6. In a clamp of the class described, a pair of flexible strips, each having a reduced

portion intermediate its ends adapting them to be crossed and connected flatly together at their ends, a housing shell for engaging the outer portions of the strips to hold them in distended position, and clamping means for engaging the connected ends of the strips for varying the size of the engaging portion formed by the inner portions of the strips.

7. In a clamp of the class described, a hollow shell having outside perforations, a pair of flexible strips having reduced portions adapting them to be crossed within the shell and the outer portions being held in distended position by the outside of the shell, the extremities being connected together outside of the shell, fastening means insertable within the connected ends for drawing them up tightly to vary the size of the clamping portion formed within the shell.

8. In a clamp of the class described, a pair of flexible strips, each having a reduced portion adapting them to be crossed intermediate their ends and to lie flatly together at their ends, a hollow perforated shell through which the ends are inserted to hold the outer portions of the strips in distended position, means for connecting the corresponding ends of the strips together and to form a perforation therethrough, and fastening means insertable through the perforations and adjustable to vary the size of the inner crossed ends of the strips.

GEORGE ARRAS.
